UNITED STATES PATENT OFFICE.

CHARLES C. HANSEN, OF EASTON, PENNSYLVANIA, ASSIGNEE TO INGERSOLL-RAND COMPANY, OF JERSEY CITY, NEW JERSEY, A CORPORATION OF NEW JERSEY.

AIR-FEED CONTROL FOR STOPERS.

Application filed May 28, 1925. Serial No. 33,403.

To all whom it may concern:

Be it known that I, CHARLES C. HANSEN, a citizen of the United States, and a resident of Easton, county of Northampton, 5 and State of Pennsylvania, have invented a certain Air-Feed Control for Stopers, of which the following is a specification, accompanied by drawings.

This invention relates to fluid actuated 10 rock drills, but more particularly to controlling devices for the air feeding element which advances the machine in accordance with the depth of penetration of the drill steel into the work.

15 One object of the invention is to enable the air feeding element to be readily controlled in an improved and simplified manner by the operator without removing his hand from the rotation handle.

20 Another object of the invention is to control admission of pressure fluid into the feeding element and to control the exhaust of pressure fluid therefrom by means of a fluid actuated valve.

25 Other objects will be in part obvious and in part pointed out hereinafter.

The invention consists of the combination 30 of elements, features of construction and arrangement of parts having the general mode of operation substantially as hereinafter described and more particularly pointed out in the appended claims and illustrated in the accompanying drawings, in which—

35 Figure 1 is a view in elevation partly in section of a stoker type rock drill constructed in accordance with the practice of the invention,

40 Figure 2 is an enlarged detail elevation-al view in section showing the air feed controlling valve in position to admit pressure fluid to the feeding cylinder,

45 Figure 3 is a view in elevation partly broken away and showing the manner in which the valve chamber communicates with the rotation handle, and

50 Figure 4 is a view similar to Figure 3 showing the valve chamber and the feeding cylinder open to atmosphere.

55 Referring to the drawings, the invention is shown embodied in a stoker type rock drill having a hammer cylinder A and a back head B held in operative position by bolts C. The cylinder A supports a front head D and the cylinder A and front head

D are held together by means of spring pressed side bolts E. Any suitable means may be provided for rotating the drill steel F supported by the front head. In this instance, a hollow rotation handle G 60 is secured to the back head B and is adapted to be grasped by the operator for rotating the drill and steel as a unit.

The feeding element comprises a feeding cylinder H which is also held in operative position by the bolts C; and a piston J, arranged to reciprocate within the feeding cylinder, carries a piston rod K which in turn supports the usual rock engaging pointer L. The cylinder H is in 70 this instance centralized by a bushing O which extends into a recess P of a valve chest Q interposed between the back head and feeding cylinder.

Pressure fluid is admitted into the drill 75 through a connection R and the admission of the pressure fluid to the cylinders is controlled by a throttle valve S having a throttle lever T. In this instance, a chamber U is formed on one side of the back 80 head to receive a spring V for holding the throttle valve to its seat.

Disposed within the cylinder A is a reciprocating hammer piston W having a rearward extension X. Air is admitted into 85 said cylinder through a port A' and constant pressure is maintained in the rearward end of the cylinder A. The distribution of the pressure fluid to the front and rear faces of the piston W through supply ports Y and Z respectively is controlled by the piston extension X. A spring pressed plunger b cooperates with a depression c formed on the throttle lever for holding the throttle valve against rotation.

In accordance with the practice of the invention a chamber d is formed in the valve chest Q to receive slidably a valve e for controlling the flow of pressure fluid to the feeding cylinder and for controlling the exhaust of pressure fluid therefrom. A passage f leading from the throttle valve to the valve chamber is controlled by the valve e and communicates with the feeding cylinder H through a series of supply ports g formed in the valve chest Q. Pressure fluid thus admitted through the passage f into the valve chamber passes around the valve through an annular groove h formed near 110

one end of said valve and through the ports 5 *g*. An exhaust port *k* formed in the valve chest between the feeding cylinder *H* and the valve chamber *d* is adapted to communicate with atmosphere through a port *o* formed near the outer end of the valve and through a passage *p* in a plug *q* screwed into the end of the valve chamber for retaining the valve within said chamber. A 10 passage *r* leading from the throttle valve to the valve chamber admits pressure fluid to said chamber for opening the valve and closing the exhaust port *k*. A spring *s* arranged within the valve *e* serves as a means for closing the valve and establishing communication 15 between the feeding cylinder and atmosphere when the pressure fluid acting against the end face *t* of the valve is exhausted.

20 In this instance, the exhaust of pressure fluid from the end of the valve chamber *d* is effected through a passage *u* communicating with a passage *v* formed through the rotation handle *G*. A passage *w* formed 25 in an extension *x* of the handle provides communication for the passage *v* to atmosphere and is controlled by a sleeve *y*. The sleeve *y* may be like that described in my copending application, Serial No. 18,375, 30 filed March 26, 1925. The amount of pressure fluid permitted to flow from the valve chamber is in this instance controlled by needle valve *z* screwed into the end of the handle *G* to cooperate with a hollow plug 35 *2* for regulating the size of the outlet opening of said plug. A nut *3* screwed on the end of the needle valve *z* serves to hold said needle valve in placed position.

In the operation of the machine, with the 40 throttle valve *S* in the position shown in the drawings, pressure fluid admitted through the connection *R* passes simultaneously to the rearward end of the cylinder *A* and through the passage *r* into the end 45 of the chamber *d* and moves the valve *e* to the position shown in Figure 2. In this position, the passage *f* is uncovered by the valve and pressure fluid passes around the valve *e* through the annular groove *h* and 50 through the spaced ports *g* into the feeding cylinder *H*. The air thus entering the feeding cylinder acts against the piston *J* and moves the drill toward the working face. It will be noted that in this position of the 55 valve *e*, the exhaust port *o* in said valve is moved out of communication with the exhaust port *k* in the valve chest. If, in case the drill steel becomes stuck in the drill hole and it is found desirable to remove the 60 drill somewhat to free the drill steel, the sleeve *y* on the extension *x* of the rotation

handle *G* may be pulled downwardly to uncover the passage *w*, whereupon a portion of the pressure fluid in the end of the chamber *d* is released and the valve *e* is moved toward the opposite end of the chamber *d*. In this manner one or more of the supply ports *g* are covered by the valve. The supply of pressure fluid to the feeding cylinder *H* is reduced and at the same time the port *o* is brought into communication with the exhaust port *k* and a portion of the pressure fluid in the feeding cylinder *H* is exhausted to atmosphere through the valve and the passage *p*.
75

I claim:

1. In a feed controlling device for rock drills, the combination of a percussive cylinder and a feeding cylinder, a back head for the percussive cylinder, a valve chest having a chamber, a hollow fluid actuated control valve in said chest for controlling the feeding cylinder, a throttle valve for simultaneously admitting pressure fluid to the cylinders and the chamber, a hollow rotation handle associated with the control valve, a sleeve slidable on said handle for releasing pressure fluid from one end of the chamber and a spring for moving the control valve in one direction.
80

2. In a feed controlling device for rock drills, the combination of a percussive cylinder and a feeding cylinder, a back head for the percussive cylinder, a valve chest having a chamber and a series of 85 spaced supply ports, a hollow fluid actuated reciprocatory valve in said chest for controlling the feeding cylinder and having an exhaust port, a throttle valve for controlling admission of pressure fluid to the cylinders and to the chamber, a supply passage leading from the throttle valve to the chamber for supplying pressure fluid to the feeding cylinder through the spaced supply ports, a second supply passage leading from the throttle valve to the end of the chamber for admitting pressure fluid to move the control valve in one direction, an exhaust port in the chest adapted to register with the port in the control valve 100 for opening the feeding cylinder to atmosphere, a spring in the control valve for bringing said ports into registration and for closing the spaced supply ports, a hollow rotation handle communicating with 105 the end of the chamber, and a sleeve slidable on said handle for releasing pressure fluid from said chamber.
110

In testimony whereof I have signed this specification.

CHARLES C. HANSEN.
